PUMP.

George H. Woodard, Phillipsburg, N. J., assignor
to Ingersoll-Rand Company, Jersey City, N. J.,
a corporation of New Jersey

Application March 20, 1935, Serial No. 11,971

2 Claims. (Cl. 230—152)

My invention relates to improvements in pumps, and particularly to means for controlling a pump when coupled to a closed vessel in which a vacuum is being created.

5 An object of the invention is to provide a self-contained unit which can be operated without the expenditure of an unduly large quantity of power at the beginning of the evacuating operation.

10 This invention belongs to the same class as that set forth in my prior patent No. 2,044,867 of June 23, 1936, entitled a Regulating device for vacuum pumps, but differs therefrom in that the pump itself is so constructed that it contains all the 15 elements necessary to yield the desired result and no accessories or external governing devices are required. When a pump is used to establish a vacuum in a closed vessel containing a fluid medium, such as air, which is to be drawn out so as 20 to establish a vacuum therein, the pump must ordinarily do much more work at the start than later, when the vacuum has been created and needs only to be maintained. The cause of this is the fact that at the outset the intake pressure 25 is high and a greater mass of air must pass through the pump and be compressed. The power required to compress the greater mass of air at high intake pressure is obviously greater than that required for a lesser mass at lower intake pressure.

30 In this invention the pump comprises a movable member, disposed in the preferred construction to revolve in a casing the intake of which can be connected to the vessel to be evacuated and the outlet of which opens to the atmosphere. The pump contains suitable passages controlled 35 by valves, preferably in the movable member, and opening to a second atmospheric outlet whenever the medium taken into the pump is compressed above a predetermined pressure, preferably as near atmospheric pressure as is practical. Hence, no matter what the intake pressure may be the mass of air being pumped during any period of operation cannot be compressed above the predetermined value and will in general have an approximately constant delivery pressure and the power consumed by the pump will remain at a fairly uniform level.

40 The nature and the advantages of the invention are fully set forth in the ensuing description, taken with the drawing and the novel features are pointed out in the appended claims. The disclosure, however, is illustrative only and variations may be made that are embraced within

the broad and general meanings of the terms in which the claims are expressed.

On the drawing, Figure 1 shows a transverse sectional view of one embodiment of a pump according to this invention.

Figure 2 is a longitudinal view through a part of the pump showing one of the outlets, and

Figure 3 is a cross-section showing a modification.

5 The numeral 1 indicates the casing or cylinder 10 of the pump which comprises also a cylindrical rotor 2, the central axis of which is eccentric with respect to the casing 1. As shown this rotor carries radial vanes 3. These vanes are mounted in slots 4 and may be normally pushed outward 15 as by springs 5 at the inner end of these slots, as well as by centrifugal force when the rotor is turning. The rotor is driven, for example, by a shaft 6 extending into one end of the cylinder 1 and the intake of the cylinder is shown at 7. 20 The working space 8 on the inside of the pump between the rotor and the casing is crescent-shaped, so that the medium entering first expands and is then compressed before it is discharged from the cylinder 1.

25 This design of pump if it has only the usual outlet at 23 on the side of the cylinder remote from the intake 7, where the space 8 contracts again, would have the disadvantage that the opening of the cylinder to said outlet would be 30 timed by the passage of the vanes over said outlet, and the compression ratio would thus be substantially constant. Hence, when the evacuating operation is commenced and the pressure of the contents of the vessel, such as a condenser, which 35 is to be evacuated so that steam or water vapor can be liquefied therein, is about atmospheric, the pump would compress the contents of said vessel as they are withdrawn to a figure much above atmospheric, say thirty to sixty pounds 40 per square inch when the pressure is about atmospheric at the inlet 7. As the contents of the vessel are progressively exhausted by the pump the discharge pressure would, of course, fall, but the ratio between the suction pressure and the 45 discharge pressure would be the same, regardless of the vacuum. Therefore, as explained in my said prior application, much power is needed when the pump begins to work to withdraw the contents of the condenser or other vessel being 50 exhausted, and later as the vacuum is established relatively little power is required to continue it.

55 My invention eliminates the large power required at the start and produces the vacuum by

the expenditure of a measure of power that is comparatively uniform and does not fluctuate materially during the operation from start to finish. For this purpose the rotor of the pump 5 has valve-controlled passages therein which open whenever the pressure rises above atmosphere and exhaust a part of the fluid from the pump. Hence, a high compression pressure is never reached whether at the start or later after 10 the vacuum has been set up.

The rotor of the pump has a central bore 9 into which the operating shaft 6 extends. The portions or sections of the rotor between the vanes 3 contain ducts 10 which extend from the periphery of the rotor inward to the bore 9. In the form shown in Figure 1 the ducts 10 may be so arranged that one or more are between each pair of vanes 3 and they have enlargements at the outer ends as indicated at 11. These ends receive plugs 12 having bores or ports 13 and at the inner ends of these plugs are valves, such as ball valves 14 engaged by springs 15 seating at the inner ends of these enlargements 11 to force the balls outward to close the ports 13. When 25 the rotor turns, the valves will be shut partly by the force of the springs 15 and partly by the centrifugal force of the valve itself.

The shaft 6 turns in a ball-bearing 16 carried in the wall of the casing 1. Over this ball-bearing 30 is a cover 17 through which the shaft 6 passes, and which is counterbored to receive packing rings 18 held by a gland 19 in this cover, around the shaft 6.

In operation when the rotor revolves the air 35 will be drawn in through intake 7 connected to the condenser or other vessel to be evacuated, and compressed in the space 8. At first the suction pressure will be relatively high, but as soon as the pressure in the space 8 between any two 40 vanes reaches the predetermined maximum pressure, the valve or valves 14 of that section will be forced open and part of the air will be discharged into the bore 9. This bore is connected to the outer air by a passage 20 and a port 21 45 in the shaft 6. As the evacuation proceeds and the pressure drops at the intake of the pump, the air in the pump will be compressed relatively higher and higher before the valves 14 open. Hence, though the compression ratio now increases, the pump now discharges a lessening 50 mass of air and the difference in power needed at the start and after the start is not very great. No heavy consumption of power when the pumping operation commences takes place, and the 55 pump runs in a most efficient and economical manner.

The shaft or trunnion 6 shown in Figure 2 will of course be matched by a similar trunnion at the opposite end of the rotor 2. Power may 60 be exerted at either end of the rotor and either or both shafts or trunnions may have passages 20 and ports 21 therein.

In Figure 3 the ball valves 14 are arranged in the bore 9 at the inner ends of the ducts 10 and 65 this bore contains a spring retainer 22 in the form of a ring which holds the balls against their seats at the inner ends of the ducts 10, but yields and permits the valves to open when the compression is great enough. With the valves at 70 the center of the pump they are held closed more by the force of the spring retainer and the centrifugal force of the valve plays a much smaller part.

75 Of course several passages 10 may be located

side by side between each pair of vanes 4, in a row extending axially or otherwise of the rotor 2.

It will be seen that, with the rotor turning anticlockwise in Figure 1, the part of the crescent-shaped space 8 between each pair of vanes 5 after leaving intake 7 constitutes a compression chamber from which most of the air is expelled as the valve 14 thereof opens. The air which remains after the pressure in the chamber has been lowered to the predetermined maximum 10 is of course discharged through the outlet 23 at whatever final pumping pressure may exist. These compression chambers, of course, revolve with the rotor 2 and the point at which the exhaust begins of course varies as the work 15 of evacuating the vessel connected to the intake 7 proceeds. At the beginning the contents of each chamber may be compressed to a sufficiently high point to enable the discharge into the atmosphere to begin just as the particular compression chamber passes through the lowest part 20 of its circular path of travel and starts upward at the right side of the pump casing 1. As the air or other gaseous medium in the intake becomes less dense and lower in pressure, the contents of each of these chambers must be compressed to a greater extent and the valve thereof will therefore not open until the chamber has been carried farther up at the right with reference to Figure 1. The point in the circle of 30 revolution of these chambers at which the exhaust commences therefore shifts as vacuum is being created.

While the pump is shown with a rotor I may also construct the pump so that the movable 35 member does not necessarily rotate, but may move in some other manner. Also whether this member rotates, or moves in a different way, the location of the valves can of course be changed without departing from the spirit of this invention.

The purpose of the invention is thus attained 45 without waste of power and without any external regulating devices being needed to work in connection with the pump. The construction of the pump is simple and in addition to the usual vanes 3 all that is needed are the passages 10, the valves 14 with their retainers to hold them normally in closed position, and the passages 9 and 20 and outlet port 21.

The presence of the conventional discharge port 23, in the pump casing 1, leading to the discharge connection 24 enables the air to be expelled efficiently after the vacuum has been established. At full vacuum in the condenser or 55 other enclosed space connected to the intake 7 there might be too much friction loss in the passages 9 and 21. The outlet 23 avoids this loss and in no way interferes with the function of the valves 14.

The air which remains in each compression chamber when the pressure has been lowered to the predetermined maximum value is of course discharged through the outlet 23, to prevent continuous expansion and compression of this 65 left over air. Hence the outlet 23 is in continuous use and may serve as a source for low pressure air if desired.

I claim:

1. A pump comprising a casing having a chamber and a movable pumping member therein, the casing having an inlet and an outlet port for fluid, the member having a discharge passage and a plurality of ducts leading from the pump chamber to the passage, and valves controlling the ducts, 70

the valves being arranged to open at a predetermined pressure of the fluid in the pump chamber to enable a part of the fluid to discharge from the pump through the ducts and passage, and 5 the said outlet being dissociated from said passage and arranged to discharge the remaining fluid from the pump at the final pumping pressure.

2. A pump comprising a casing having an inlet and outlet port for fluid, a movable pumping 10 member in the casing having means forming a plurality of pumping chambers in the pump, the member containing a discharge passage and a

plurality of ducts leading from the chambers to the passage, valves controlling the ducts, and spring members controlling the valves, the valves being arranged to open at a predetermined pressure of the fluid in the pump to enable part of the fluid to discharge from the chambers through the ducts and passage, and the said outlet port being dissociated from said passage and arranged to communicate with each chamber to discharge the remaining fluid from the pump at the final 10 pumping pressure.

GEORGE H. WOODARD.
